UNITED STATES PATENT OFFICE.

HENRY ARTHUR FRASER AND PETER FREDERICK CRIGHTON, OF LONDON, ENGLAND.

WEAVING OF COILED WIRE FABRICS AND MACHINE THEREFOR.

Application filed August 27, 1921. Serial No. 495,986.

To all whom it may concern:

Be it known that we, HENRY ARTHUR FRASER and PETER FREDERICK CRIGHTON, subjects of the King of Great Britain, residing at 13, Wharf Road, N. 1. London, England, have invented new and useful Improvements in the Weaving of Coiled Wire Fabrics and Machines Therefor, of which the following is a specification.

10 This invention relates to machines for weaving plain coiled wire fabrics such, for instance, as are used for mattresses, and to machines of the kind having mechanism for coiling and severing the wire to form the 15 strands and provided with a pair of parallel horizontal rollers having longitudinal flutes, grooved or ribs designed to grip the fabric between them and capable of rotary and longitudinal movement so that the fabric 20 is moved or positioned to bring the last made coil or coils or strands into the proper position to receive the next coil, or coils or strands.

In machines of this type it has been proposed 25 to arrange the grooved or fluted rollers with their axes in a horizontal plane and so that the last made coil or strand of the fabric is gripped between two of the opposed grooves of the rollers and held in this position 30 whilst the next coil or strand is run into it above the rollers which are rotated to feed the fabric downwardly. This arrangement, however, possesses the defect that the end of the running in coil or strand 35 will, owing to gravity, be likely to foul the upper edges of the opposed grooves of the grooved rollers gripping the last made coil, even if the said end does not foul the end of one or other of the said rollers, which 40 it has a tendency to do.

The object of our invention is to obviate the said disadvantages and to this end we arrange the parallel grooved or fluted rollers for gripping and positioning the fabric 45 one above the other, and in such a position with respect to the coiling mechanism that the last made coil or strand with which the running in coil engages is next to the coil gripped by the said rollers and is held rigid 50 by such gripping action, means being provided for supporting the running in coils when engaging the said last made coil and means for assisting to feed the fabric in correspondence with the rotary feed movement 55 of the grooved rollers in the event of the

said rollers not extending the full length of the fabric.

In a suitable construction of machine, coiling mechanism is provided in which the feed rollers therefor preserve a constant relation 60 and are intermittently driven from a pulley through the medium of clutch mechanism, hereinafter termed the main clutch. This clutch is operated by a lever, hereinafter termed the controlling lever, connected to 65 another lever, the said controlling lever being maintained in the operative position by a catch against the pull of a spring. This catch is disengaged from the controlling lever to stop the feed rollers of the coiling 70 mechanism by a rack-bar which is caused to move longitudinally by gearing driven by another clutch mechanism which is itself thrown into gear by the controlling lever simultaneously with the main clutch, means 75 being employed whereby the duration of its movement to strike the catch can be varied according to the length of coil or strand required.

The said rollers are carried on centres in 80 claw frames or housings hinged together and drawn towards one another by springs and supported upon a slide designed to impart longitudinal movement to the said rollers by a lever from a suitable cam. This cam is 85 carried upon a shaft operable by a wheel through the medium of worm-gear, the said wheel being driven by the driving pulley of the machine by a friction pulley or roller moved into contact with the belt thereon 90 by means such as toggle levers operated by the controlling lever. The said shaft also carries a cam for imparting the required intermittent rotary or feed motion to the positioning rollers through the medium of 95 lever and ratchet and pawl mechanism. Two more cams are carried upon the said shaft, one for effecting the severing of the wire or wires through the medium of lever mechanism and the other for effecting the operation of the controlling lever so as to operate the main clutch. This latter operation is effected by the lever connected to the controlling lever and hereinbefore referred 100 to on to which is dropped a weight supported 105 by a cord or the like wound upon a sleeve loose on the lower shaft of the coiling gear and coiled thereon, when the said shaft is rotated, by a friction clutch controlled by the last mentioned cam.

For starting the machine we arrange a lever hereinafter termed the starting lever designed, when in its normal position, to hold the controlling lever in an intermediate position but which, when moved, allows the said controlling lever to be moved by a spring so as to place the friction pulley or roller hereinbefore described into position to drive the shaft carrying the cams. This 10 starting lever is held in the starting or running position against the pull of a spring by a pivoted latch which can be released to stop the machine either directly by hand, or electrically by a solenoid controlled by a 15 short circuiting device operated by the coiled wire becoming deformed the core of the solenoid being connected by a rod to the said latch.

To enable the invention to be fully understood, we will describe it by reference to the accompanying drawings, in which:—

Figure 1 is a plan of a machine constructed according to the invention for manufacturing or weaving coiled wire fabrics and

25 Figure 2 is an elevation of a portion of the same.

Figure 3 is a horizontal section on the line 3—3, Figure 2.

30 Figure 4 is a view of the right hand side of the machine and

Figure 5 is a sectional view of a part of the opposite side thereof.

Figure 6 is a rear view of the machine and

35 Figures 7, 8 and 9 are respectively vertical sections on the line 7—7, 8—8, and 9—9, of Figure 6, certain parts being omitted from each of these figures for the sake of clearness.

40 Figure 10 is an elevation of a portion of the frame of the machine showing some of the bearings.

Figure 11 is an enlarged section on the line 11—11, Figure 1, illustrating clearly the 45 positioning rollers.

Figure 12 is an elevation showing the falling weight and lever operated thereby.

Figure 13 is a section of a modified form of positioning roller.

50 Figure 14 is a sectional view of one of the friction clutches.

Figure 15 is a view of a piece of coiled wire fabric of single ply plain weave as made by the machine and

55 Figures 16 and 17 are views illustrating different stages in its manufacture.

Figure 18 is a diagram illustrating the order of working of the cams employed to effect this plain weave.

60 *a* is the frame or base of the machine provided with three standards *a*¹, *a*², *a*³. Between the standards *a*², *a*³ are arranged the feed rollers for the coiling mechanism and comprising the upper plain roller *b* and the 65 lower grooved roller *b*¹, the peripheries of

which rollers revolve nearly in contact with one another. The said rollers are geared together so as to run at equal speeds by means of rings of spur teeth *b*². *c* is the wire to be coiled and which is drawn from a spool in the usual way and may be in one, two or more plies, the said wire or wires lying in the groove *b*⁴ in the roller *b*¹, and being gripped therein by pressure of the top roller *b* thereon, and fed into the coiling die *c*¹ of usual or known form. The top roller *b* is supported upon a shaft *d* carried in bush bearings *e*, *e*¹ in the standards *a*², *a*³, respectively. The bush *e* is held in position in a recess *e*² in the standard *a*² and is pressed upon its upper part by a rubber block *e*³ to which pressure can be imparted by set-screws *e*⁴ through the medium of a plate *e*⁵ the said screws passing through the cap *e*⁶. The bearing *e*¹ is supported in a recess *e*⁶ in the standard *a*³ and can be adjusted therein through the medium of set-screws *e*⁷ to impart the necessary pressure to the wire *c* (or wires). A rubber block *e*⁸ is advantageously interposed between the bush *e*¹ and a covering cap *e*⁹ connected to the upper part of the standard *a*³. The roller *b*¹ is supported on a shaft *f* arranged in bearings in the standards *a*¹, *a*² and designed to be rotated to effect the rotation of the rollers *b*, *b*¹ from a shaft *f*¹ supported in bearings at the top of the said standards *a*¹, *a*² through the medium of a train of three gear wheels *f*². The said shaft *f*¹ has connected thereto one member *f*³ of a friction clutch, the other member *f*⁴ of which is loose on the said shaft and is in the form of a pulley which is constantly rotated by a suitable belt and when pressed into contact with the member *f*³ effects the rotation of the rollers *b*, *b*¹. The members *f*³, *f*⁴ constitute the main clutch and have arranged between them a spring *f*⁵.

g is the controlling lever pivoted at one end by a shaft *g*¹ to the standard *a*¹, the said shaft being provided with arms *g*² which engage holes in lugs *g*³ on a disc *g*⁴ mounted loosely on the shaft *f*¹ and bearing against the pulley *f*⁴, so that, when the said lever *g* is rocked in one direction on its pivot, the member *f*⁴ of the main clutch will be pressed into contact with the other member *f*³. *g*⁵ is the catch for holding the controlling lever *g* in position after it has effected the pressing together of the two members of the main clutch, the said catch which is pivoted at *g*⁶ to the standard *a*², engaging, under the pull of a spring *g*⁷, a hooked projection *g*⁸ on the lever *g*, the said lever being held in this position against the pull of a spring *g*⁹. The coiling gear is designed to be intermittently driven and to enable this to be effected, we provide means for disengaging the catch *g*⁵ from the hook projection *g*⁸ on the controlling lever *g*. For this purpose, we provide the horizontal bar 130

5 *h* slidably supported in a guide *h*¹ carried on the standards *a*¹, *a*² and having rack teeth *h*² in mesh with a pinion *h*³, as shown clearly in Figure 3. This pinion is rotated by a clutch, preferably in the form of a split 10 tapered sleeve *h*⁴, Figures 3, 5 and 14, fitted within a central hole in the said pinion and formed on, or attached to, a gear-wheel *h*⁵, the latter meshing with a worm *h*⁶ on the shaft *f* and being carried in a bearing in a piller *h*⁹. Within the split sleeve *h*⁴ is fitted a taper pin *h*⁷ designed to be moved within the sleeve *h*⁴ so as to expand the latter into tight contact with the hole in the 15 pinion *h*³, this movement being imparted by a downward extension *h*⁸ on the controlling lever *g*. When the pressure of the said extension is removed from the pin *h*⁷, the sleeve *h*⁴ will contract and so become disengaged 20 from the pinion *h*³.

25 The rack-bar *h* is moved by the pinion *h*³ to disengage the catch *g*⁵ against the pull of a weight *h*⁹ through the medium of a cord *h*¹⁰ running over a pulley *h*¹¹. *h*¹² is a set-screw for determining the starting position 30 of the rack-bar *h* so that the duration of the movement of the said bar *h* to strike the catch *g*⁵, can be varied according to the time at which it is required to run the coiling gear and consequently the length of coil or strand produced.

35 The coiled wire is fed from the die *c*¹ around the grooved mandrel *c*² in the known manner, the end of the said mandrel forming one surface *c*³ of a pair of cutting surfaces, the other one *c*⁴ of which is movable and supported and carried by a lever *c*⁵ actuated as hereinafter described. This lever is pivoted at *c*⁶ to a bracket *c*⁷ carried on the 40 frame *a*, the said bracket also serving for supporting the mandrel *c*².

45 *i*, *i*¹ are the positioning rollers arranged horizontally, one above the other, with a space between them to grip each coil in turn of the fabric being made, the said rollers being located with their axes parallel to the axis of the coiled wire lying between the mandrel *c*² and the coiling die *c*¹, but out of line therewith and just beyond the rear end 50 of the mandrel *c*², as indicated in Figure 1, so that, say, after three coils of wire have been issued from said mandrel in succession and linked with one another, the third coil, as indicated clearly in Figure 11, will be located between the positioning rollers *i*, *i*¹, so that the latter can, by rotating in the direction of the arrows, feed the fabric to receive fresh coils in turn, as hereinafter described. The coils as they issue from the mandrel *c*² 60 run on to the table A, the upper surface of which is level with the upper surface of the lower roller *i*.

65 The rollers *i*, *i*¹ are provided with the ribs *i*² arranged longitudinally so as to grip the coils as indicated in Figure 11; or they may

be formed spirally as hereinafter described. Figure 13 is a cross section of one of the positioning rollers in which fins *i*³ are substituted for the ribs *i*². *i*¹, *i*² are the housings in which the rollers *i*, *i*¹ are carried on centres *i*⁴, these housings being hinged together as indicated at *i*⁵, Figure 9, and drawn towards one another by springs *i*⁶ attached at one end to lugs on the housing *i*² and at the other end to the base *a*. *j* is the slide upon 70 which the housings carrying the rollers *i*, *i*¹ are mounted so that longitudinal movement can be imparted to the said rollers for positioning the fabric so that the new or running coil is engaged with the coils already made at the proper point according to the class of fabric being made. This slide works in guides *j*¹ on the frame *a* and is actuated from a cam *j*² in the form of a rib on a drum *j*³ through the medium of a lever *j*⁴ 75

adjustably pivoted to the frame *a* at *j*⁵. This cam is carried on a shaft *k* mounted in bearings *k*¹ on the frame *a* and driven by a worm-wheel *k*² on the shaft *k* from a worm *k*³, carried on a shaft *k*⁴ mounted in bearings 80 in the standards *a*¹, *a*². This shaft *k*⁴ carries a friction wheel *k*⁵ designed to be driven from the pulley *f*⁴ through the medium of the friction roller *k*⁶, which is brought into contact with both the belt on the pulley 85 *f*⁴ and the wheel *k*⁵ by a pair of toggle levers *k*⁷, *k*⁸. These levers are slidably supported on fulcrum pins *k*⁹ on the standard *a*² and jointed together at *k*¹⁰, the outer end of the lever *k*⁷ carrying the roller *k*⁶, whilst the 90 outer end of the lever *k*⁸ is pivoted to the controlling lever *g*. It will thus be seen that when the controlling lever is moved upwardly it disengages the main-clutch members *f*³ and *f*⁴ and at the same time moves 95 the friction roller *k*⁶ into contact with the driving belt *f*⁹ surrounding the pulley *f*⁴ and thus drives the wheel *k*⁵ and consequently rotates the cam-drum *j*³.

100 For rotating the positioning rollers *i*, *i*¹, the lower roller *i* is provided at its front end with ratchet teeth *l*, as shown clearly in Figure 11, corresponding in number with the ribs *i*² thereon, so that the said roller can be fed or rotated one rib at a time, in order to 105 displace the coiled fabric laterally, one coil at a time. *l*¹ is a pawl engaging with the said ratchet teeth and carried on a short lever *l*² pivoted on one of the centres carrying the roller *i*, the said lever being oscillated by a pin *l*³ on a bell crank lever *l*⁴ actuated by a cam *l*⁵ carried on the drum *j*³, the said bell-crank lever being fulcrumed on the frame *a* by a shaft *l*⁶ which also carries an arm *l*⁷. This arm *l*⁷, through the medium of 110 a pin *l*⁸, rocks another arm *m* to impart movement to a bar *m*¹ resting on the table A which bar forms a guide for the running coil and assists the rollers *i*, *i*¹ to feed the fabric after each coil is inserted. This feeding 115 120 125 130

movement is effected simultaneously with the feed movement of the said rollers i , i' through the movement of the said arms l^1 , l^2 from the bell-crank lever l^4 , the arm m^1 being fulcrumed on a shaft m^2 carrying upstanding arms m^3 which bear against one side of the bar m^1 and actuate the latter to feed the fabric against the pull of tension springs m^4 .

10   n is the cam for effecting the severing of the coils, after being run on to the table A , by means of the cutting surfaces c^3 , c^4 . This cam actuates a lever n^1 , Figure 8, fulcrumed at n^2 to the bracket c^1 and bearing 70 upon a lug n^3 on an upright rod n^4 pivoted at n^5 to the lever c^3 . The rod n^4 slides and is guided in a hole in the frame a and is pressed upwardly in contact with the lever n^1 by a spring n^6 .

15   20   In order to keep the running coil in contact with the bar m^1 we employ an electromagnet m^5 , the faces of the pole-pieces m^6 of which are level with the guide surface of the said bar m^1 . This magnet is energized, 75 each time a coil is run into the fabric, by a switch in the form of a drum m^7 carried upon the shaft k and having a pair of contacts m^8 with which a brush m^9 in electrical connection with one terminal of the magnet 80 makes contact twice in each revolution of the shaft k . These contacts m^8 are in permanent electrical connection by a brush m^{10} with one pole of a source of current the other pole of which is in electrical connection with the other terminal of the magnet. 85

30   o is a cam for automatically effecting the movement of the controlling lever g to throw in the main clutch to drive the coiling gear and stop the rotation of the cam-shaft k . This cam actuates a lever o^1 fulcrumed at o^2 to a lug on the frame a and connected at its upper end by a rod o^3 to a lever o^4 pivoted at o^5 to the standard a^2 , the cam o moving the rod o^3 against the 90 pressure of a spring o^6 located between the end of the said rod o^3 and a bracket o^7 attached to the frame a . This lever o^4 , until actuated by the cam o , presses against the taper pin p of a clutch mechanism similar 95

40   50   to that described in connection with the pinion h^3 . This pin p is located in a hole formed in one end of the shaft f , the said end being split and formed taper to fit the pin p and has fitted on its outer surface a loose sleeve p^1 to which is attached a cord p^2 carrying at its lower end a weight p^3 , shown clearly in Figure 12. Below the weight p^3 is arranged a lever p^4 hinged to the floor p^5 , or to a suitable part of the machine, and connected by a cord or wire p^6 to the outer end of the controlling lever g . The pressure of the spring o^6 causes the pin p to expand the split end of the shaft f to grip the sleeve p^1 and, assuming that the 100 cord p^2 is wound upon the sleeve, as indicated in the drawings, and the cam o be caused to actuate the lever o^4 to relieve the pressure on the pin p , the friction between the split end of the shaft f and the sleeve p^1 will consequently be relieved, and allow 105 the latter, under the influence of the weight p^3 , to be revolved so that the weight will be lowered and strike the lever p^4 , which, through the medium of the cord p^6 , will lower the controlling lever g against the pull of the spring g^8 and connect the members of the main clutch so that motion is imparted to the coiling gear, the said lever g being held in the lowered position by the engagement of the catch g^5 with the hooked extension g^7 . 110

15   20 g is the lever for starting the machine, which lever is of bell-crank form pivoted at g^1 to the upper part of the standard a^2 and in the stopped position bears against the controlling lever g and holds it in an intermediate position, as indicated in Figure 5, in which the roller k^6 is out of contact with the belt f^0 . The said lever g is provided with a stop-pin g^2 which, in the said stopped position, holds the catch g^5 in such a position that it cannot engage with the hooked extension g^7 . By moving the said lever g to the dotted line position in the 115 said Figure 5, it will be seen that the controlling lever g will be free to rise under the pull of its spring g^8 , so that the toggle levers k^1 , k^2 will be moved to cause the friction roller k^6 to engage with the pulley belt f^0 and wheel k^5 , thereby effecting the rotation of the shaft k and causing the cam o to move the lever o^4 to release the weight p^3 and through the medium of the lever p^1 and cord p^6 to lower the controlling lever g into engagement with the catch g^5 . The 120 shaft k will thus cease rotating on the disengagement of the roller k^6 with the wheel k^5 and belt f^0 , and the pulley f^4 will be caused to engage with the member f^3 so that the coiling gear will be rotated to deliver a running coil on to the table A . 125

20   25   The starting lever g is held in the dotted line position by a pivoted latch r against the pull of a tension spring g^9 , the said latch having a notch r^1 in which engages a projection r^2 on the starting lever g , so that it is necessary, when stopping the machine, that the latch r be lifted in order that the starting lever g may be drawn to the full line position under the influence of the 130 spring g^8 . This stopping operation is also automatically effected if the wire being coiled should issue from the coiling mechanism deformed, and for this purpose we employ a solenoid s , the core s^1 of which is connected by a rod s^2 to the latch r and a stud s^3 is mounted on the standard a^2 but insulated therefrom and which is in electrical connection with one pole of a source of current as indicated in Figure 5. The starting 135

lever g is provided with an insulated contact piece which, when the said lever is moved to the dotted line position, makes contact with the said stud. In front of the 5 coiling die c^1 is arranged a shield in the form of a semicircular piece of sheet metal c^3 with which the deformed wire is designed to contact and which is carried on but insulated from the standard a^2 and in electrical 10 connection by a wire s^4 with the insulated contact on the lever g . One terminal of the solenoid is connected to the other pole of the source of current whilst the other terminal is connected to the frame, as indicated. 15 Assuming the machine to be running, the lever g being in the dotted line position, if the wire being coiled should become deformed so that it touches the shield c^3 , current will circulate through the stud s^3 , the 20 contact on the lever g , the wire s^4 , the said shield, the coiling die c^1 and the frame a to the solenoid s so that the core s^1 will be sucked into the latter and lift the lever r .

In the drawings we have shown all the 25 cams as formed with two cam surfaces diametrically opposite one another, so that each cam will function twice during one revolution of the shaft k . The arrangement also applies to the drum m^7 .

30 For the production by the machine of a one ply plain single weave fabric as indicated in Figure 16, assume that two coils t and t^1 have been successively delivered by the coiling mechanism, the first one t being positioned by hand to allow the proper engagement therewith of the other coil t^1 in the known manner, and assume the two coils to have been moved laterally so that the positioning rollers i, i^1 engage with the coil t 35 in the manner indicated in Figure 11 whereby the said coil t and the coil t^1 are securely held against movement, the cut ends of the two coils being in the position indicated with relation to the cutting surfaces c^3, c^4 . Assume, now, that the machine is running and that the coiling mechanism has again delivered a coil or strand of wire from the mandrel c^2 , as indicated by the dotted lines at t^2 , Figure 16, the rack bar h having made 40 contact with the catch g^5 so as to release the controlling lever g and consequently disengage the parts of the main clutch and stop the coiling gear and at the same time commence the rotation of the cam shaft k . By referring to Figure 8, it will be seen that the 45 said shaft rotating in the direction of the arrow, one of the cam surfaces on the cam n will operate the lever n^1 to effect the cutting of the coiled wire by the cutting surfaces c^3, c^4 . The positioning rollers i, i^1 will now be caused to rotate by one of the cam surfaces t^5 , to feed the fabric the distance of one coil to the right and afterwards to be positioned or moved longitudinally to 50 correspondingly move the fabric towards the

cutting surfaces c^3, c^4 so that the coils t, t^1, t^2 take up the position indicated in Figure 17, in which position the coil t^2 is in the correct position to receive the next running coil, it being rigidly held by a pair of the opposed ribs i^2 on the rollers i, i^1 . The next feeding and positioning movement of the rollers i, i^1 will move the fabric away from the cutting surface c^3, c^4 into position to receive the next coil and so on, the resultant 70 fabric being indicated clearly in Figure 15. To assist in maintaining the coils in their proper relative positions longitudinally, the first five coils, say, are pierced by the teeth u of a horizontal comb connected by a frame u^2 to the lower housing i^4 . The order of action of the cams for producing the fabric shown in Figure 15 is indicated diagrammatically in Figure 18, the cams n, t^5, j^2 and o acting, respectively, to effect the cutting 75 off of each coil, the partial rotation or feed movement of the rollers i, i^1 . The longitudinal movement of the latter and the releasing of the weight p^3 to stop the cams and start the coiling mechanism, these movements taking place twice during the rotation of the shaft k .

In the drawings it will be noticed that the fabrics therein shown are made of single 80 ply, that is of one wire only for each coil, but it is to be understood that two or more wires can be employed for each coil.

Having now particularly described and ascertained the nature of our said invention and in what manner the same is to be performed, we declare that what we claim is:—

1. A machine of the kind hereinbefore referred to for the manufacture of coiled wire fabrics, comprising coiling mechanism grooved rollers for gripping and positioning 105 the fabric, rollers being arranged with their axes one above the other and in such a position with respect to the coiling mechanism that the last made coil or strand, with which the running in coil engages, is next to the 110 coil gripped by the said rollers and is held rigid by such gripping action and are provided means are provided for supporting the running in coil when engaging the said last made coil.

2. A machine as claimed in claim 1, including means for assisting in feeding the fabric in correspondence with the rotary feed movement of the grooved rollers in the event of the latter not extending the full length 120 of the fabric and further means for guiding each running in coil into position with respect to such auxiliary feeding means.

3. A machine as claimed in claim 1, including means for assisting in feeding the fabric in correspondence with the rotary feed movement of the grooved rollers in the event of the latter not extending the full length 125 of the fabric and further means, including an electro-magnet, for guiding each running 130

in coil into position with respect to such auxiliary feeding means.

4. A machine of the kind claimed in claim 1, wherein a comb is employed having the 5 pitch of its teeth corresponding with that of the turns of the wire coils and passing between the grooved positioning rollers in engagement with a series of the said coils.

5. In a machine as claimed in claim 1, 10 gear mechanism for operating the feed rollers for the coiling mechanism, the said gear mechanism being controlled by a clutch actuated by an intermittently operated controlling lever for feeding the wire to the 15 coiling mechanism.

6. A machine as claimed in claim 1, gear mechanism for operating the feed rollers for the coiling mechanism, the said gear mechanism being controlled by a clutch actuated 20 by an intermittently operated controlling lever for feeding the wire to the coiling mechanism, means whereby the controlling lever is held in position for effecting the coiling of the wire and wherein timing mechanism is employed whereby the said lever is released when a sufficient length of wire 25 has been coiled.

7. A machine as claimed in claim 1, gear mechanism for operating the feed rollers for 30 the coiling mechanism, the said gear mechanism being controlled by a clutch actuated by an intermittently operated control-

ling lever for feeding the wire to the coiling mechanism, means whereby the controlling lever is held in position for effecting the coiling of the wire and wherein timing mechanism is employed whereby the said lever is released when a sufficient length of wire 35 has been coiled, means operated by a falling weight to move the controlling lever 40 to start the coiling mechanism, cams on a shaft for effecting the operations of severing each coil, for imparting rotary and longitudinal movement to the positioning rollers and releasing the said weight, means operated by one of the shafts of the coiling mechanism, feed wheels to lift the weight so that the controlling lever is moved after 45 being released from the holding means; and means whereby such movement of the controlling lever effects the rotation of said cam shaft.

8. In a machine as claimed in claim 7, the combination with the controlling lever of a stopping and starting lever designed when 55 in the stopping position to hold the said controlling lever in a position in which the clutch mechanism and friction roller controlled thereby are disengaged and also to disengage the means for holding the controlling lever whilst the wire is being coiled, substantially as described.

HENRY ARTHUR FRASER.
PETER FREDERICK CRIGHTON.

Certificate of Correction.

It is hereby certified that in Letters Patent No. 1,431,645, granted October 10, 1922, upon the application of Henry Arthur Fraser and Peter Frederick Crighton, of London, England, for an improvement in "Weaving of Coiled Wire Fabrics and Machines Therefor," an error appears in the printed specification requiring correction as follows: Page 5, lines 112 and 113, claim 1, strike out the words "are provided", both occurrences; and that the said Letters Patent should be read with this correction therein that the same may conform to the record of the case in the Patent Office.

Signed and sealed this 2d day of September, A. D. 1924.

[**SEAL.**]

KARL FENNING,
Acting Commissioner of Patents.
